UNITED STATES PATENT OFFICE

WILLIAM H. BAUCH, OF SHELBYVILLE, INDIANA, ASSIGNOR OF ONE-HALF TO ORVAL R. PLATTER, OF NORTH VERNON, INDIANA, AND ONE-HALF TO SONO EQUIPMENT CORPORATION, OF INDIANAPOLIS, INDIANA, A CORPORATION OF INDIANA

METHOD AND APPARATUS FOR REPRODUCING SOUND

Application filed September 20, 1929. Serial No. 394,110.

This invention relates to the art of recording and reproducing sound such as speech, music or other sounds or waves, and particularly to photographically recording sound on a film and reproducing it therefrom. The invention is primarily designed to be used in connection with motion pictures in which it is desired to synchronize music or speech with the picture which is being projected.

In general the object of the invention is to provide new and improved apparatus for so-called talking pictures which will be simple in construction and in operation.

Referring to the accompanying drawings, which are made a part hereof and on which similar reference characters indicate similar parts,

Figure 1 is a perspective view of a motion picture machine showing my sound reproducing apparatus applied thereto,

Figure 2 is a perspective view of the driving mechanism for the machine,

Figure 3 is a section on line 3-3 of Figure 2,

Figure 4 is a view in elevation on an enlarged scale of the sound reproducing unit,

Figure 5 is a perspective view of a detail as seen from line 5-5 of Figure 4,

Figure 6 is a plan view of the light unit as seen from line 6-6 of Figure 4,

Figure 7 is a section on line 7-7 of Figure 4,

Figure 8 is a diagrammatic view showing the lamp, the slit, and the lenses for focusing the light on the light sensitive slit and on the film, and

Figure 9 is a view of a portion of picture and sound film.

In the drawings reference character 10 indicates a picture projecting machine of any well known construction in which numeral 11 indicates the reel from which the film is unwound during projection of the picture and numeral 12 the reel on which the film is wound, these reels and the mechanism for operating them being well-known in motion picture production. Numeral 13 indicates the film which in this case is provided with the usual notches 14 by means of which it is driven with a sprocket wheel 15 and is

provided also with a narrow margin 16 along its edge upon which the sound record is photographically impressed.

Shown as a whole in Figure 4 is the sound reproducing unit. This consists of a shaft 16 on which the sprocket wheel 15 is mounted, the shaft extending out of a housing 17 and having a grooved pulley 18 on its outer end. The shaft 18 also preferably is provided with a pinion 19. A motor 20 has a motor shaft 21 on the end of which are mounted a grooved pulley 22 and a pinion 23. A plurality of belts 24 provide driving connection between the pulleys 22 and 18 and an idle pinion 25 provides driving connection between the pinion 23 and the pinion 19. The shaft 16 is therefore driven both through a belt and a positive gear drive. The purpose of this driving connection is to give a positive drive and at the same time a noiseless drive, the belts 24 acting to cushion the driving contact between the pinions. I may find it desirable at times to dispense with the gear drive and drive wholly through the plurality of belts 24. I find this belt drive very effective since by using a plurality of belts I am insured a perfect drive since the tendency of any one belt of the groups to slip will be overcome by the remaining belts furnishing a constant drive; this therefore provides a constant speed drive for the shaft 16 to give a constant speed to the film which passes through the machine. In reproducing sound, of course, it is very necessary that the film run at a constant speed in order to give the desired even tone to the sound or music which may be in the process of being reproduced by the machine. Secured within the casing 17 is a roller 26 around which the film 13 passes in order to have the film engage the sprocket wheel 15 through a relatively long arc to prevent injury to the film by providing greater friction contact with the sprocket wheel. The film also engages a roller 27 upon entering the sound reproducing casing and passes between a pair of rollers 28 from which it passes to the reel 12 upon which it is wound. An arm 29 is pivoted at 30 to the casing 17 and has on its outer end a

- shaft 31 upon which a roller 32 is mounted, the shaft 31 being held to the arm 29 by means of set screw 33. A bracket 34 secured to the back of the casing 17 has an adjustable stop screw 35 threaded through its end for engagement by the arm 29. A bracket 36 secured to the casing has a leaf spring 37 secured upon it, the end of the leaf spring engaging a corner 38 on the end of the arm 29 to hold the arm 29 against the stop 35 to position the roller adjacent the sprocket 15 to hold the film in position to be engaged by the sprocket wheel 15 to drive it through the machine.
- 15 When in operation, during the reproduction of sound picture the film 13 will pass between the roller 32 and sprocket 15 and around the roller 26, thence back between the rollers 28. When it is desired to operate a film other than a talking film, the film will engage the outer side of the roller 32 as shown in dotted lines in Figure 4 in which position it is held out of contact with the sprocket 15 and passes directly through the rollers 28 to be wound on the reel 12. The arm 29 may be swung down past the leaf spring 37 when it is desired to insert a new film in the machine.
- 30 The apparatus for reproducing sound from the record previously made upon the film will now be described. This consists of a barrel 39 in which are positioned a series of lenses 40, 41, 42 and 43. Intermediate the lenses 41 and 42 are positioned plates 44 and 45 positioned apart so as to leave a very narrow slit 46 between them. These plates are secured to an inner flange 47 on the cylinder 39 by means of screws 48. The screws 48 pass through holes in the plates 44 and 45 which are slightly larger than the screws so as to allow the plates to be adjusted toward and from each other to vary the width of the slit 46. Set screws 49 and 50 are threaded through the outer wall of the barrel and rest against the outer edge of the plates 44 and 45 in order to adjust the plates toward each other to vary the width of the slit. The slit 46 may be in the neighborhood of three or four thousandths of an inch in width. I do not, however, limit myself to any particular width. The lens 41 is positioned with respect to the slit 46 so that the light from a lamp 51 is brought to a focus at the slit. The edges of the plate 44 and 45 are beveled to provide a knife edge, as shown at 52, at which point the light is brought to a focus. The barrel 39 is secured in the casing in a bracket 53, which is split and has lugs through which is threaded a tightening screw 54. The barrel may therefore be adjusted axially of the bracket and secured in adjusted position. A bracket 55 is secured to the casing 17 by means of screws 56.

This bracket has a slit 57, the forward side of the slit being chamfered off to provide a very thin portion to the bracket at the point of the slit. The lamp 51 is held in a socket 68 which socket is secured in a holder 58 which is adjustable toward and from the barrel 39 in a bracket 59. The holder 58 is screw threaded on its ends and has nuts 60 by means of which it is adjusted vertically with respect to the barrel 39 and locked in adjusted position. A contact wire 61 is secured in the holder 58 and is attached to a suitable source of current of the proper voltage for the lamp. The holder 58 is flattened on opposite sides, as shown at 62, to hold it against turning in the bracket 59. The bracket 59 is also adjustable laterally of the barrel 39 by means of pins 63 and 64 which are secured in a bracket 65, these pins engaging in sockets in bracket 59. A set screw 66 holds the bracket 59 in its laterally adjustable position so as to position the light 51 in the proper relation to the lenses in the barrel 39. The socket holder 58 is provided with a set screw 67 by means of which the lamp socket 68 may be adjusted so as to position the filament 69 in the lamp in the proper position. A bracket spring 70 provides means for holding a cover 71 to protect the lamp and its parts. The barrel 39 has an opening in its side covered with a glass 72 positioned adjacent the plates 44 and 45 so that the operator may see just when the light is properly focussed on the slit 46. A bracket 74 is secured to the housing 17 by means of set screws 75. This bracket carries pins 76 upon which a light sensitive cell socket holder 77 is mounted to slide. A socket 88 is held in member 77 and carries a light sensitive cell 78. This cell may be any suitable cell which is sensitive to light so that it will be conductive only when light is shining upon it and in which the resistance varies in accordance with the intensity of the light that is projected upon it. Such cells are well-known and need not be further described. We have found potassium cells operate efficiently. The member 77 has tension springs 79 secured to it at one end which springs are secured at their other end to bracket 74, these springs tending to withdraw the member 77 to its rear-most position. A lever 80 has a cam surface 81 cut to engage a cam surface 82 on the member 77. By means of the cam surfaces 81 and 82 operation of the lever 80 moves the member 77 toward the bracket 55 against the back of which bracket the film 13 is moved. The forward end of the member 77 is provided with a frame 83 which is spring pressed toward the bracket 55 which frame engages the back of the film to hold the film steady against the back of the bracket 55. The frame 83 is pressed toward

the bracket 55 by means of a leaf spring 84. The light sensitive cell 78 is connected by means of wires 85 and 86 with a battery 87 of suitable voltage and leads to the sound 5 reproducing mechanism. It may be necessary under most circumstances to amplify the current a number of times, however, I do not limit myself to a machine in which the output is amplified for I may find it 10 possible, under advantageous circumstances, to reproduce the sound in the ordinary way without amplifiers.

It will be obvious to those skilled in the art that various changes may be made in my device without departing from the spirit 15 of the invention and therefore I do not limit myself to what is shown in the drawings and described in the specification, but only as indicated in the appended claims.

20 Having thus fully described my said invention, what I claim as new and desire to secure by Letters Patent, is:

1. In an apparatus for reproducing sound from a film on which a record has been 25 made, a lamp, a barrel having focussing lenses enclosed therein and spaced apart, slides positioned in said barrel and adjustable toward each other to provide a slit at their adjacent edges, the slit being positioned at the focus point of adjacent lenses, and a perforation in said barrel closed by 30 transparent slide to enable an operator to see when the light is focussed on the slit, substantially as set forth.

35 2. An apparatus for reproducing sound from a film on which a record has been made in terms of light and shadow, said machine having electric pick-up instrumentalities, a light sensitive cell for varying the electric 40 current passing through said instrumentalities, a bracket adapted to receive said cell, means for adjusting said bracket and securing it in predetermined adjusted position relative to the said film, said adjusting 45 means comprising a cam engageable with the said bracket, substantially as set forth.

50 3. The combination with a picture projecting machine of a sound reproducing device comprising means for projecting a beam of light through that portion of the film on which sound has been previously recorded in terms of light and shadow, electric pick-up instrumentalities for transforming light 55 variations into sound waves, a light sensitive cell for varying electric current passing through it in said instrumentalities, a bracket adapted to receive said cell, a cam on said bracket, a manually operable lever having a cam thereon engageable with the first 60 named cam, resilient means biased to move said bracket away from the path of said film, said manually operable means serving to adjust said cell and secure it in adjusted position with relation to said film, 65 substantially as set forth.

In witness whereof, I have hereunto set my hand at Shelbyville, Indiana, this 13th day of September, A. D. nineteen hundred and twenty-nine.
